UNITED STATES PATENT OFFICE.

CHARLES R. WALTER AND JACOB E. BLACKBURN, OF FREDERICKTOWN,
OHIO.

WHIFFLETREE.

SPECIFICATION forming part of Letters Patent No. 315,361, dated April 7, 1885.

Application filed December 11, 1884. (No model.)

To all whom it may concern:

Be it known that we, CHARLES R. WALTER and JACOB E. BLACKBURN, citizens of the United States, residing at Fredericktown, in the county of Knox and State of Ohio, have invented certain new and useful Improvements in Spring Attachments for Whiffletrees, of which the following is a specification, reference being had therein to the accompanying drawings.

This invention relates to spring-whiffletrees; and it consists in the parts which will be hereinafter described, and pointed out in the claims.

15 In the accompanying drawings, Figure 1 represents a top plan view of a whiffletree provided with our improvements. Fig. 2 is a like view, enlarged, of one end of the whiffletree with improvements attached. Fig. 3 20 is a rear view of the parts shown in Fig. 2.

In the three views the rear ends of the traces are shown secured to the casting on the outer end of the spring.

The letter A represents the whiffletree, provided on its outer ends with thimbles B. Said thimbles are each provided with a T-shaped head, C, having a slot, C', therein for the reception of the trace D. The trace passes through this slot, and it is attached to the outer end of a spring, to be hereinafter specified.

E represents a casting provided with a longitudinal face-recess for the reception and retention of the inner end of the bar-spring F. 35 The outer side of the casting E conforms to the surface contour of that portion of the whiffletree with which it is brought in contact.

E' indicates a bridge or cross-piece on the casting E, under which the inner end of the spring F rests.

G indicates a threaded bolt and nut for securing the spring in its seat in the casting E. The spring is provided with an opening 45 through which the bolt passes.

G' represents the clinched head of the bolt. The bolt passes through the spring, casting E, and whiffletree. The outer end of the spring F is provided with a trace-catch, F'. The 50 outer end of this catch has an enlarged flat

head to prevent the trace from slipping off the end thereof. The thimble B is provided with a projection, H, on the rear side. This projection is to limit the forward movement of the spring when the traces are drawn forward. The thimble, slotted head C, and projection H are formed integral, although the head C may be separately formed with a screw-point, whereby it may be screwed into the outer end of the whiffletree. The normal position of the spring is about an angle of forty-five degrees from the longitudinal plane of the whiffletree. The object of this is two-fold: First, it prevents a shock when the traces are suddenly drawn forward, and, secondly, 65 it draws back on the traces when the vehicle is descending a hill, or the horses back. This spring, under those conditions, keeps the traces taut and prevents the trace-loops from disengagement with their respective catches. 70

Having thus described our invention, what we claim as new, and desire to secure by Letters Patent, is—

1. A whiffletree provided on its outer end with a slotted head for the reception of the 75 trace, a spring having one end secured to the whiffletree and the other end extending outward and provided with an enlarged head, substantially as described, and for the purposes set forth.

2. A whiffletree provided on its outer end with a thimble, slotted head, and projecting spring-stop, said whiffletree being also provided with a bar-spring having its inner end secured thereto, the outer end of said spring 85 having an enlarged head, substantially as and for the purposes set forth.

3. A whiffletree provided on its outer end with a slotted head, the recessed casting E, and the bar-spring F, having the enlarged 90 head-piece, the parts being united and secured in the manner and for the purposes specified.

In testimony whereof we affix our signatures in presence of two witnesses.

CHARLES R. WALTER.
JACOB E. BLACKBURN.
